Primary Examiner — Michelle E. Wilson(57) **CLAIM**

I claim the ornamental design for a release paper for wound treatment devices, as shown and described.

DESCRIPTION

FIG. 1 is an underside plan view of an ornamental release paper for wound treatment devices in accordance with the present invention showing our new design;

FIG. 2 is a top plan view thereof;

FIG. 3 is a front elevation thereof;

FIG. 4 is a rear elevation thereof;

FIG. 5 is a left side elevation thereof; and,

FIG. 6 is a right side elevation thereof.

The broken lines showing the environment in the drawings is for illustrative purposes only and forms no part of the claimed design.
